UNITED STATES PATENT OFFICE.

SVEND MARTIN MEYER, OF BROOKLYN, NEW YORK, ASSIGNOR OF ONE-HALF TO FRANK C. KOHART, OF BROOKLYN, NEW YORK.

ELECTRIC-ARC LAMP.

SPECIFICATION forming part of Letters Patent No. 693,041, dated February 11, 1902.

Application filed March 12, 1901. Serial No. 50,785. (No model.)

To all whom it may concern:

Be it known that I, SVEND MARTIN MEYER, a subject of the King of Denmark, and a resident of Brooklyn, in the county of Kings and State of New York, have invented a certain new and useful Improvement in Arc-Lamps, of which the following is a specification.

This invention relates to improvements in electric-arc lamps, and has for its object the production of an arc-lamp in a simple form and of a construction such that it will burn on an incandescent-lamp circuit and may be as readily connected into such circuit as an incandescent lamp. An arc-lamp of this sort, provided with a length of flexible conductor and suitable "plug," may be moved about from room to room and connected up to any socket of an incandescent fixture, thus enabling it to be used on a table as a "drop-light" or supported in any desired manner in a room. An incandescent electrolier may be readily equipped with my improved arc-lamp, and of course it may enter into any regular arc-lamp installation.

The invention consists in the construction, combination, and arrangement of parts hereinafter fully described, and set forth in the claims.

In the accompanying drawings, which form a part of this specification, Figure 1 represents, in partial vertical section, one form in which my improvements in electric-arc lamps may be embodied. Fig. 2 represents a horizontal section through the lamp mechanism, taken on the line 2 2, Fig. 1, the upper part of the casing having been removed. Fig. 3 is a partially-sectionized elevation of a portion of the lamp-frame. Fig. 4 shows in perspective a connector by means of which the lamp may be placed in circuit with any incandescent-lamp fixture.

As above stated, the lamp is well adapted for a drop-light, and it has been shown in that form. The mechanism of the lamp may be mounted in any suitable frame. In the structure shown said frame consists of the lower plate 5, the upper plate 6, connected to the lower plate by supports 7, and the guide-rods 8, mounted upon the plate 6. Upon the plate 6 and centrally located in respect thereto and insulated therefrom is a lower-carbon

holder 9, the lower carbon 10 being secured therein by a set-screw, as 11. The upper-carbon holder is shown at 12, and consists of a suitable socket for receiving the upper carbon 13 and guides at the sides thereof, which are located upon the guide-rods 8. This carbon-holder is joined by a flexible connection, such as a chain, (indicated at 14,) to a differential pulley 15, journaled between one of the uprights 7 and a bracket, as 16, depending from the plate 6. To the smaller sheave of the pulley 15 is connected, by a flexible connection 17, a solenoid-core, as 18, which is movably suspended in the solenoid 19, attached to or otherwise suitably supported beneath the plate 5. The weight of the core 18 and that of the carbon-holder 12 are so proportioned that the latter shall slightly overbalance the former, thereby tending constantly to settle the upper carbon upon the lower carbon.

One of the essential features by which the mechanism of my improved lamp is simplified is a magnetic clutch. This clutch I so construct and locate that it shall engage the core 18 to regulate the descent thereof, and therefore the separation of the carbons, in striking the arm. The magnetization of the core 18, induced by the circuit flowing in the coil 19, is depended upon for the operation of this clutch. To this end the clutch consists of a tilting platform 20, mounted upon the plate 5 between posts 21, and the clutch members 22, pivoted upon this platform, as seen in Fig. 2. These clutch members are provided with jaws, preferably conformed to the contour of the core 18, and are normally withdrawn from said core by means of a spring 23 joining their rearward ends. Also there is located between the clutch members an adjusting-screw 24, the under side of whose head is conical, as seen in Fig. 1, whereby the distance between the jaws of the clutch and the rod 18 may be regulated. The platform 20 is preferably made to rest normally upon a stop-screw 25, and for this purpose its rearward end is preferably weighted so as to overbalance the weight of the jaws of the clutch. The weight for accomplishing this purpose may be produced by thickening the platform at the rear of the supports 21, as clearly in-

dicated in Fig. 1. Normally, then, the platform will rest upon the stop-screw 25. Its tilting movement under the action of the core 18 when drawn into the solenoid may be regulated and limited in any suitable manner—as, for instance, by the screw 26, which has a collar thereon, as shown at 27, with which the platform shall engage as it is tilted. The platform is shown in tilted position by dotted lines in Fig. 1.

Any suitable cut-out switch may be used in the circuit of this lamp, and a simple form for such switch is illustrated, whereof one contact is shown at 28 as mounted upon and insulated from the plate 6, said contact being preferably connected to the binding-post to which the circuit 29 of the lamp is connected. The movable contact for engagement with the contact 28 is shown at 30 and is attached to 20 and operated by the rod 31, journaled in a lug depending from the plate 6 and in the side of the nut 32, by which the lower-carbon holder is held in place.

The circuit of the lamp 29, just referred to, 25 extends from one of the protruding lamp-terminals (seen at 32, Fig. 1) to plate 6 of the lamp-frame. Thence the current passes to the upper carbon through the frame, thence through the lower carbon to the rod 31 of the 30 switch, and when the switch is closed from contact 30 on said rod to contact 28, and thence by conductor 29 to and through the coil 19 to the rheostat 33 in the base of the lamp, whence said circuit leads to the other terminal 32. 35 The controlling-lever of the rheostat may project from the base of the lamp, as shown at 34. This lamp operates perfectly well as an “inclosed-arc” lamp and is shown in the drawings provided with the arc-inclosing globe 35.

40 A convenient mode of connecting the lamp to an incandescent or other fixture is illustrated in Fig. 4, wherein an ordinary incandescent-lamp plug is represented at 36 joined to a connector 37 by means of flexible conductors 38, said connector consisting of two metallic tubes located in a piece of fiber or other insulation and adapted to engage with the protruding terminals 32 of the lamp.

When the lamp is connected in circuit and 45 the switch 31 closed, the core 18 is immediately attracted and starts into the solenoid; but immediately following this starting of the core it, by virtue of the magnetism induced therein by the coil, attracts the jaws of the 50 clutch, which limits the downward movement of the core to the distance required for producing the necessary separation of the carbons, the extent of the downward movement of the core, and therefore the separation of the 55 carbons, being regulated in the main by means of the screw 26 and the adjustable stop 25. This regulation is further refined by means of the screw 23, since thereby is determined the distance that the jaws of the clutch must 60 travel before they can engage the core 18, and therefore the distance that the core 18 can travel after switch 31 is closed before it is

grabbed by the clutch. Therefore by means of these three screws 23, 25, and 26 a very even and accurate adjustment of the length 70 of arc may be obtained. When the carbons have burned away sufficiently to demagnetize the core 18, (which is preferably of low magnetic quality,) the clutch will release the core and the weighted carbon-holder will cause 75 the carbons to come together, whereupon the action above described in striking the arc will again take place.

In a lamp of the structure shown and described a small and short solenoid is sufficient 80 for the feeding operation, and it will be noted that the coil performs two functions—namely, that of a choke-coil or resistance in the lamp-circuit as well as that of attracting and magnetizing the core 18.

85 Many changes may be made in the manner of mounting the essential features of my lamp and in the form and construction of such means of mounting, and many changes may likewise be made in the form and arrangement of the parts constituting said essential features, without departing from my invention.

90 I claim as my invention—

1. In an electric-arc lamp having a coil in 95 the circuit of the carbons, a core in said coil, a carbon-holder connected to said core, and a magnetic clutch energized by said coil and engaging said core to control the movement of the carbon-holder.

100 2. An electric-arc lamp having a coil in the circuit of the carbon, a movable core in said coil and connected to one of the carbon-holders, and a magnetic clutch grasping said core and controlling the movement thereof.

105 3. An electric-arc lamp having a coil in the circuit of the carbon, a movable core in said coil and connected to one of the carbon-holders, a magnetic clutch engaging said core and actuated by said coil to control the feeding of 110 the carbons.

115 4. In an electric-arc lamp, a coil in the circuit of the carbons, a magnetizable core in said coil connected to a movable carbon-holder, and a clutch consisting of pivoted magnetic members attracted to the core through the action of said coil and grasping it to regulate the feed of the carbons.

120 5. In an electric-arc lamp, a coil in the circuit of the carbons, a core of low magnetic quality suspended in said coil connected to a movable carbon-holder, and a tilting clutch having pivoted iron jaws for engaging said core to regulate the feed, said core being magnetized by current in said coil to attract said 125 jaws for the purpose set forth.

130 6. In an electric-arc lamp, a solenoid having a movable core connected to a movable carbon and a magnetically-actuated feeding-clutch for engaging said core and controlling the feed.

135 7. In an electric-arc lamp, a solenoid having a movable core connected to a movable carbon, a tilting platform, clutch members of

soft iron pivoted thereon, and a spring tending to hold the clutch open, said clutch being attracted into engagement with the core when the solenoid is energized.

5 8. In an electric-arc lamp, a feeding mechanism consisting of a solenoid having a movable core and a tilting clutch magnetically actuated to engage said core and controlling the movement thereof, the magnetic influence 10 arising from the current in the solenoid.

9. The combination with the movable carbon-holder, of the solenoid, the movable core of the solenoid, the tilting platform, the pivoted clutch members thereon for engaging 15 said core, means for regulating the movement of the platform, and means for adjusting the distance of the clutch members from the core, for the purpose set forth.

10. The combination with the movable carbon-holder, of the differential pulley, the solenoid, the movable core of the solenoid, the

flexible connection between the core and pulley and carbon-holder, and the magnetic clutch for engaging said core.

11. The combination of an ornamental casing provided with a base for supporting it, a rheostat in said base, circuit-terminal contacts protruding from the base, an arc-lamp frame supported in said casing and insulated therefrom, a globe inclosing the upper part 30 of said frame and the arc-producing parts and supported on the casing, and a removable flexible connection for attachment to said terminals, for the purpose set forth.

Signed at New York, in the county of New 35 York and State of New York, this 8th day of March, A. D. 1901.

SVEND MARTIN MEYER.
